COMBINED BRUSH AND CASE

Walter Henkels, Mangenbergerstrasse 264,
Solingen-Merscheid, Germany

Filed Aug. 16, 1960, Ser. No. 61,782

Claims priority, application Germany Mar. 2, 1960

Term of patent 14 years

(Cl. D9—2)

FIG. 1 is a perspective view of a combined brush and case in open position incorporating my ornamental design;

FIG. 2 is a top plan view thereof in the closed position;

FIG. 3 is a side elevational view thereof;

FIG. 4 is a rear elevational view thereof;

FIG. 5 is a front elevational view thereof; and

FIG. 6 is a sectional view taken on the line 6—6 of FIG. 2.

The implements shown in broken lines in FIG. 1 are for illustrative purposes only, the invention being shown in solid lines.

I claim:

The ornamental design for a combined brush and case, substantially as shown and described.
